US00D873798S

(12) **United States Design Patent** (10) **Patent No.:** **US D873,798 S**
(45) **Date of Patent:** **** Jan. 28, 2020**

(54) **COMMUNICATION DEVICE**

(71) Applicant: **SONY MOBILE
COMMUNICATIONS INC.**

(72) Inventor: **Keita Hibi**, Tokyo (JP)

(73) Assignee: **SONY MOBILE
COMMUNICATIONS INC.**, Tokyo
(JP)

(**) Term: **15 Years**

(21) Appl. No.: **29/638,103**

(22) Filed: **Feb. 23, 2018**

Related U.S. Application Data

(63) Continuation of application No. 29/622,128, filed on Oct. 13, 2017, which is a continuation of application No. 29/555,302, filed on Feb. 19, 2016, now Pat. No. Des. 801,950.

CLAIM

The ornamental design for a communication device, as shown and described.

DESCRIPTION

FIG. 1 is a perspective view of a first embodiment of a communication device showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and

FIG. 7 is a bottom plan view thereof.

FIG. 8 is a perspective view of a second embodiment of a communication device showing my new design;

FIG. 9 is a front elevational view thereof;

FIG. 10 is a rear elevational view thereof;

FIG. 11 is a left side elevational view thereof;

FIG. 12 is a right side elevational view thereof;

FIG. 13 is a top plan view thereof; and,

FIG. 14 is a bottom plan view thereof.
